UNITED STATES PATENT OFFICE.

ARTHUR J. BOLFING, OF SAN FRANCISCO, CALIFORNIA.

VOTING-MACHINE.

SPECIFICATION forming part of Letters Patent No. 696,932, dated April 8, 1902.

Application filed March 26, 1896. Serial No. 585,025. (No model.)

To all whom it may concern:

Be it known that I, ARTHUR J. BOLFING, a citizen of the United States, and a resident of the city and county of San Francisco, State of California, have invented certain new and useful Improvements in Voting-Machines, of which the following is a specification.

These improvements relate to suitably-protected means for mechanically accumulating on the counters of the respective candidates the votes given for each candidate whether or not said candidates are on the regular list of any party, usually called a "straight ticket," and similarly to the registry of what is termed 15 a "split ticket" and also to a complete registry of the poll for all candidates.

The invention consists in various devices, as set forth in the accompanying drawings, in which—

20 Figure I represents in perspective a broken view of a polling-booth arranged to receive the improved voting and registering apparatus. Fig. II is an enlarged view in perspective of a portion of the voting and registering mechanism to the line xx in Fig. I. Fig. III is a section through the operating mechanism for voting substitute or scratch names, also in part the mechanism for voting regular or straight tickets. Fig. IV is a transverse section looking to the left on the line yy in Fig. III, showing the operating elements before any votes have been registered by this mechanism. Fig. V is a similar section showing the same mechanism after one scratch or substitute vote has been registered by this mechanism. Fig. VI is a plan view in section of the mechanism shown in Fig. III with the covering-plates and some of the mechanism omitted. Fig. VII is a broken section corresponding in the main elements to Fig. III, but provided with the additional devices required when more than one and some predetermined number of candidates are to be voted for any given office. Fig. VIII is a 45 front or end view of the mechanism shown in Fig. VII, taken at a right angle thereto. Fig. IX is a vertical section through one of the units or elements containing the voting mechanism for complete or straight tickets. 50 Fig. X is a side view of one of the links seen in edge view in the plan view, Fig. XI. Fig. XI is an edge view of the mechanism shown

in Fig. X. Fig. XII is a horizontal section on the line zz of Fig. IX. Fig. XIII is a broken section through Fig. IX on the line aa . Fig. XIV is an enlarged detail of the mechanism shown in Fig. I, showing the mechanism for readjustment of the voting and registering mechanism as each voter enters the voting-booth. Fig. XV is an edge view of the mechanism shown in Fig. XIV. Fig. XVI is a view showing key 22 of Fig. IX depressed with its train of mechanism in a corresponding position. Figs. XVII, XVIII, and XIX are views showing details of Figs. 65 IX, XII, and XVI. Fig. XX is an isometric view of some of the elements contained in the lower half of Fig. III, showing one of the bars 39 in an operated position as having been moved forward by the rod 13, key 22, and connecting accessories of Fig. XVI. Figs. XXI and XXII are views showing the means for cutting out connection between the individual-candidate mechanism and the straight-ticket mechanism. Fig. XXIII is an isometric illustration with portions of the casing and such of the parts broken away as to show as clearly as may be the relation of all the operating parts. Figs. XXIV to XXIX, inclusive, relate to multicandidate mechanism, also shown in Figs. VII and VIII, Fig. XXIV being an isometric view with casing and parts broken away to show means for returning ratchet-wheel 49 to normal position. Fig. XXV shows means for raising pawls 85 clear of ratchet-wheel 49 to permit its return to starting-point. Figs. XXVII and XXVIII are enlarged front and edge views of ratchet-wheel 49, showing some of the details of the multicandidate mechanism. Fig. XXIX is 90 an enlarged isometric view of a detail shown by dotted lines in Fig. XXIV.

Similar numerals of reference are employed to designate like parts in the several figures of the drawings.

The general object of this invention is to attain certain functions that will be pointed out at the end of this specification and in the claims appended thereto by certain mechanical means, the principal elements of which are a series of oscillating rods or shafts operated by depressible keys, these keys corresponding to the various contesting political parties, such keys actuating counters,

- one for each candidate, also supplemental means for operating the same counters for substitute or scratch names or candidates, and at the same time cutting out or omitting the remainder of the counters for candidates for the same office, so that when an elector has thus voted for a particular candidate selected from some group or party the registering-counters for that candidate cannot be again operated when the elector subsequently votes for the party group of his preference.
- To this end there is provided a voting booth 1, as seen in Fig. I, along one side of the interior of which is arranged a plank 2, upon which the voting mechanism, to be hereinafter described, is fastened. To this booth 1 there are provided two doors, the entering-door 3, connected with the voting mechanism, and a door 4, by which the voters leave the booth 1. The voting and registering mechanism is disposed in units or elements 5, 6, 7, and 8 and as many additional as there are offices to be voted for, as seen in Fig. II, the width of each or the number of names and depressible keys 21 22 being made to conform to the requirements in elections to be held, the whole row or tier of these elements being traversed by actuating-rods 9, 10, 11, 12, 13, and 14, one of these rods 9 being, as before explained, connected with the entering-door 3 in such a manner that when the door is opened to admit a voter the voting machinery is restored to original adjustment, or the elements operated by the preceding voter are restored to their normal position and ready for new and independent voting and registry. If the space provided for these sections or units is not occupied, a covering 2^a of the required length is provided, so the rods 10 11 12 13 14 cannot be injured or tampered with.
- At the back of the voting machinery and over the counting elements is a perforated plate 15, through which the registry of the counters 16 can be seen, as in Fig. II. Over this plate 15 is placed a sheet or plate of glass 17, through which the figures on the counters 16 can be read, and over this I place a removable covering-plate 18, that is secured in place while the voting proceeds.
- At one side of the booth 1 there are swinging doors 19 20, the one, 19, opening downward to form a shelf or desk, on which notes from the counters 16 or the result of the poll can be made up, the upper door 20 when raised or opened affording a full view of the interior of the booth and the mechanism therein.
- The function of the rod or shaft 9 is to unlock the depressible keys 21 22 and the mechanism connected therewith, so they will return to their original position after an elector has voted. This rod 9 is operated by the door 3, which in opening is slid back into the chamber 23 between the panels 24 25, as seen in Figs. I, XIV, and XV.
- On the end of the rod 9 is placed a crank 26, operated by a sliding bar. (Seen enlarged in Figs. XIV and XV.) When the door 3 is

opened or moved back, the end of the bar 27 engages a plate 28 on the edge of the door 3 and is carried back until the crank 26 has been moved the required distance. Then the angular portion 29 of the bar 27 reaches the bearing 30, causing the bar 27 to rise until disengaged from the plate 28. Then the spring 31 returns the crank 26 and the bar 27 to their original position, the stop 32 coming in contact with the bearing 30, as seen in Figs. XIV and XV.

The description this far has been confined to the views shown in Figs. I and II and the details thereof in Figs. XIV and XV or to the external operating elements involved in the application of this invention, and I will now proceed to describe the registering mechanism contained in the elements 5, 6, 7, and 8 in Fig. II.

Referring now to Figs. III to VI, inclusive, Fig. III is a longitudinal section through one of the units or elements 5, 6, or 7, (seen in Fig. II,) 21 being one of the voting-keys and 16 the counters. These latter I do not describe because of the common decimal type and a well-known article of manufacture. These counters are operated by a pivoted member 33 in the form of a bell-crank, turning on the axis 34 and provided with a pawl 35, that engages a ratchet-wheel 36 on the first of the counting-wheels 16. This bell-crank 33 can be operated in two ways—by the hinged lever 37 and also by a pawl 38 on the sliding bar 39. These bars 39, of which there is one for each of the keys 21, are operated by the rods 11, 12, 13, and 14 of a semicircular section, so arranged that when turned they will engage the lugs 40 on the under sides of the bars 39 and push these bars forward, the pawl 38 engaging and turning the bell-crank 33 and counting one by the ratchet-wheel 36. The rod 10 has a different function to perform, as will be explained in a future place. The number of the semicircular rods may be increased or diminished, as may be required by circumstances. The bell-crank 33 after it has acted on the ratchet-wheel 36 is restored to its first position by the spring 56, and the bars 39 after acting and release are returned by springs 57. For each counter 16 there is provided a spring 58, the end of which acts as a detent for the ratchet-wheel 36, and the other end bears on the center counter-wheel at 59, as seen in Fig. III, so as to prevent lost motion. The third counter-wheel is also similarly held by an extension of the spring 57, that presses at 60, so as to cause some friction, but not positive resistance. There are as many of the sliding bars 39 as there are names or candidates and counters 16, and the lugs 40—one on each bar 39—are so set that all the bars registering for the candidates of one party will be operated by one of the semicircular rods 11, 12, 13, and 14. For example, suppose the rod 11 to be operated by the key 22 opposite the name "Republican" in Fig. II, then the lugs

40 on all the slides 39 operating the counters for Republican candidates will be set on the bars 39, so as to be engaged by the rod 11. So of the rod 12, all the bars 39 registering for Democratic candidates will be provided with lugs 40 to engage the rod 12, so the lugs 40 are staggered in position, one on each bar 39, set to engage one of the rods 11 12 13 14.

5 If a candidate has the official indorsement or nomination of two or more of the contesting parties, there will be provided lugs 40, one for each party so nominating or indorsing, and placed in such position on bar 39, (operating the counter of said candidate,) so 15 as to engage with the respective rods 11, 12, 13, or 14 corresponding with the parties giving such official indorsement or nomination.

The connection between the voting-keys 22 and the oscillating bars 11, 12, 13, and 14 will 20 be explained subsequently in connection with Figs. IX to XII.

Adjacent to the individual-candidate keys are placed the names of the candidates. To facilitate and assist the elector in voting a 25 split ticket to locate the keys of the candidates for whom he may desire to vote, respective voting-numbers are placed adjacent said keys, thereby identifying said keys with said candidates. Where candidates have been officially assigned voting-numbers, the placing 30 of the candidate - names upon the machine may be dispensed with, the voting-numbers being in lieu thereof. With this arrangement it will readily be seen that rearrangement of 35 said machines for subsequent elections will be greatly facilitated.

Continuing with Figs. III to VI, I will now proceed to explain the means for voting a split ticket. It was pointed out that the bell-crank 33 was operated in two ways—by the 40 sliding rods 39 and pawls 38 and also by the levers 37. The latter are pivoted at 34 and when moved downward by the tappets 41 on the keys 21 turn at the same time the bell-crank 33, operating the counters 16 the same as by the action of the sliding bars 39 and the rods 11, 12, 13, and 14. When any of the 45 levers 37 are depressed, they come in contact with and turn the hinged angular stop-bar 50 42, forcing it down upon the flexible pawls 38, thereby holding the ticket mechanism in that section out of engagement with said bell-cranks. Disks 47 are thrust laterally by the depression of the lever 37, thereby preventing the depression of another lever 47. Hence it will be seen that but one bell-crank in the section can be operated. These angular stop-bars 42 extend across the width of each of the sections or elements 5, 6, or 7 acting on all the pawls 38 and cutting out all the bars 39 in that section. When the levers 37 are depressed, a pawl 43, operated by the 55 springs 44, falls into the angular groove 45 in the rod 9, thus locking the levers 37 in their depressed position and holding the pawls 38 out of contact. The keys 21 when released by the voter are instantly raised by the coil-

springs 46, that bear under the tappets 41, as seen in Fig. III.

In Figs. III to VI the mechanism is shown 70 as arranged for one substituted or scratched vote in each group. This limit is imposed by the pendulous disks 47, hinged or pivoted between the slots 48, as seen in Figs. IV and V and hereinafter called "wards." In Fig. IV 75 these wards 47 are shown in their normal position, and in Fig. V they are shown in their position after one of the levers 37 is depressed and one vote given. In this latter position it will be seen the wards 47 are swung right and 80 left by the depressed lever 37 closing or warding all the remaining slots 48, so that no other of the levers 37 or keys 21 can be depressed until the wards 47 are restored to their original position, as seen in Fig. IV. These wards 85 47 abut one against the other and move in combination to the right and left from any one of the levers 37 that is passed between them, as shown in Figs. IV and V and also in Fig. XIII. When the substituted or 90 scratched votes, if any, are given, the elector then passes on to the keys 22, that operate the counters for groups of candidates forming the straight tickets of the respective parties. This mechanism is illustrated in 95 Figs. IX, X, XI, and XII, which will be subsequently referred to and explained. As, however, in some cases more than one candidate is to be voted for in an office, provision is made for this in the manner indicated in Figs. 100 VII, VIII, and XXIV to XXIX, inclusive. In that case the pendulous or hinged wards 47 are placed on the opposite side of the end plate 74 and are employed to close the slots 48, as in the previous case, but with this difference that they are moved or swung laterally by the tappets 41 on the stems of the keys 21. These pendulous wards, as previously explained, abutting one against the other, act on a ratchet-wheel 49 by means of a 110 pawl 50, attached to the end ward 47, as indicated by dotted lines in Fig. VIII, so that when either of the keys 21 is depressed the wards 47 are moved laterally, and the pawl 50 moves the ratchet-wheel 49 one tooth. Ratchet-wheel 115 49 is loosely pivoted on 49^c. Attached to said wheel 49 is a fixed stop 51, resting normally against permanent stop or pin 51^a, fixed in plate 74. Holes 52 in plate 74 are set radially around ratchet-wheel 49 in the 120 range of movement of stop 51 and so spaced that a pin 52^a can be set at various positions around the wheel 49, corresponding with the teeth thereon, and thus form a limit to the 125 number of keys that can be depressed and the number of votes that can be given in that section or group. Spring 49^b, one end of which is attached at inner end of stop 51 and the other end made fast to fixed pivot 49^c, serves to return the ratchet-wheel 49 to normal position when pawls 50 and 50^a are raised by the action of pawl 43^a and rod 9 upon an elector entering the booth. The function of pawl 50^a is to prevent retroactive movement

130

of wheel 49 after it has been partially revolved by the action of pawl 50. The ends of pawls 50 and 50^a rest normally upon wheel 49 and are raised therefrom to allow the 5 turn of wheel 49 to normal position by means of projections 43^c and 43^d on angular pawl 43^a. Pawl 43^a is pivoted at 43^e. Upon the operation of rod 9 point 43^b thereof is forced out of groove 45, thus raising the ends 43^c and 43^d, and consequently pawls 50 and 50^a, to a 10 position clear of the teeth on ratchet-wheel 49. It will be observed that the ends of the pawls 50 and 50^a rest partially on the wheel 49 and project partially over its edge, so that 15 the ends 43^c and 43^d will when operated come in contact with and disengage said pawls from said ratchet-wheel, as aforesaid.

The sectional view for Fig. IX is taken through element 8 in Fig. II, the one whereby 20 the rods 11, 12, 13, and 14 are operated to vote for a complete group or straight ticket of one party. The depressible keys 22 are severally connected with the oscillating rods 11, 12, 13, and 14 by means of the levers 53, mounted on a fulerum at 54 and depressed by pins 55 in the stems 73 of the keys 22, and are held down when depressed by the detaining or locking rod 9 and pawl 43 the same as in Fig. III and already described. On the faces 25 of the oscillating rods 11, 12, 13, and 14 are attached cross-bars 62, having eyes to receive the pins 63 on the links 64 66, as shown in Figs. X and XI, shorter pins 65 on the same links engaging the lever 53, as seen in Figs. 30 IX and XII, except in the case of rod 12, which requires only a pin 65, projecting into a slotted hole 75 in the lever 53, to accommodate the arc of movement. In this manner the four keys 22 and corresponding levers 53 35 are severally connected with or engage the four oscillating rods 11 12 13 14, and these rods in turn each engage certain of the sliding bars 39, as seen in Fig. III, each rod operating one group of counters for the candidates of a certain party, as before explained. When one 40 of the keys 22 is depressed with a corresponding lever 53, the pawl 43 engages in the groove of the rod 9, holding the lever 53 down, the key 22 rising again automatically by means of 45 the coil-spring 67. As the lever 53 descends it passes between the hinged disks or wards 68, (seen in front view at Fig. XIII,) swinging these to the right or left and closing the slots 69 the same as in the case of the levers, 50 (shown in Figs. III, IV, and V,) so that but one key 22 can be depressed by each voter, the others being locked by the wards 68. These levers 53 when either one of them is depressed performs the further office of locking all the 55 keys 21 in the following manner: On the oscillating rod 10 is fastened a bar 70, that is engaged by the extension 71 of the lever 53, and the rod 10 is thus turned so its flat face will stand at the angle as shown by dotted lines in Figs. III and VII, and in that position prevents any of the keys 21 from being 60 depressed after the voter has registered for 65

the remainder of the candidates in the party of his preference by keys 22. When the levers 53 are released by the rod 9 and the pawls 70 43, they are raised and reset by the coil-spring 72, the wards 68 falling back to the position seen in Fig. XIII.

From description thus far given it will be seen that by turning the rod 9, operated by 75 the entering-door 3 in the booth 1, that all the levers 57 and 53, the sliding bars 39, with their connected accessories, will resume their first or normal position, ready for the cycle of operations that have been described. 80

To render the method of voting and the operation of the mechanism more clear, I will now follow through the whole, explaining how an elector will cast and register his votes. First he or an officer in charge will open the 85 door 3, which, as hereinbefore explained, will set all the various elements of the machinery in proper position for a new vote. If the elector wants to vote a straight ticket—that is, for a complete group of candidates of one 90 party—he passes by the keys 21 and presses down one of the keys 22 opposite to the name of the party of his choice, as seen in Fig. II. This turns one of the rods 11, 12, 13, or 14, as the case may be, and by acting on certain of 95 the slides 39 registers one vote for each candidate of this particular party in the elements 5, 6, or 7. (Seen in Fig. II.) No other of the keys 22 can be depressed by reason of the wards 68, and the elector can thus vote for but one 100 party. At the same time by depressing either of the keys 22 he locks all the keys 21 by means of the oscillating rod 10. If, however, the elector does not want to vote a straight or complete ticket for one party, he stops before 105 the elements 5, 6, or 7 and presses down one of the keys 21 for some candidate of his choice in another group or party, counting one vote for the same, and by means of the angular stop-bar 42 depresses all the pawls 38 in that 110 element or for the group of candidates for that office, cutting out connection between that group and the keys 22. Then the voter proceeds to the keys 22 and votes for the party of his choice, except for the substituted candidate previously voted for and cut out by the keys 21. In this manner it will be seen that the votes given will be registered with absolute certainty.

Among the results attained by the use of 120 this machine are the following: The votes will be registered simultaneously with the indication of the elector's preference of candidates. The total number of votes cast for each candidate are shown. The manner of 125 operating the machine is so simple that the process is at once apparent to the elector. The balloting is conducted with the utmost secrecy and without the liability of interference or intimidation of the elector, thereby 130 conduced to the purity of elections. The elector is prevented from identifying the votes cast by him to interested parties or to persons desiring to fraudulently influence voters. In

this way an honest vote may be had and the purity of elections conserved. An elector cannot vote for a candidate more than once nor for two candidates for the same office; but 5 an elector may vote for two candidates or for any predetermined number of candidates where the law contemplates he may so do, and a straight ticket may be voted by the operation of a single key. A split ticket may be 10 voted in which a portion of the votes may be registered through the medium of the individual-candidate keys and a portion by a ticket-key, the votes being properly accumulated upon the counters of the candidates, 15 respectively, for whom they were cast.

Having thus described the nature and objects of my invention, I claim—

1. In a vote-recording machine, means for resetting the mechanism, said means comprising a grooved rod, said rod adapted to release or reset the operated parts; a latch-bar connected with said rod to impart movement thereto, said latch-bar adapted to be tripped after being moved a predetermined distance, 25 substantially as described.

2. In a voting apparatus, sections or units placed in series, one section having a series of straight-ticket keys, other sections having a series of candidate-keys and counters; flattened 30 oscillating rods traversing said sections, said rods operated by the straight-ticket keys and acting on said counters; means independent of said rods, controlled by the candidate-key and acting on said counters, whereby votes 35 may be cast for individual candidates without affecting the straight-ticket mechanism, substantially as specified.

3. In a voting apparatus, a series of sections; said sections provided with counters; 40 respective individual-candidate keys for operating said counters; a straight-ticket section; said section provided with keys for operating such of said counters as were not cut out by substitution by said individual-candidate keys.

4. In a voting apparatus, sections or units placed in series, each provided with depressible voting-keys and counters, one section comprising straight-ticket keys, other sections 50 comprising keys and counters for individual candidates or measures, flattened oscillating rods passing through all the sections, each rod operated upon by a straight-ticket key, said rods operating the aforesaid counters, 55 and independent means for operating said counters controlled by the individual-candidate keys; in combination therewith, a rod passing underneath the individual-candidate keys and the levers of the straight-ticket section, so that when said levers are operated the individual-candidate keys will become locked against operation.

5. In a voting apparatus, a series of individual-candidate sections, each provided with 60 keys, levers and counters, a straight-ticket section provided with keys and levers, oscillating rods traversing all said sections and

operated by said straight-ticket keys, one of said rods locking the individual-candidate keys and the remainder of said rods operating 70 counters, means independent of said oscillating rods operated by the individual-candidate keys and operating the said counters, and a series of pendulous disks or wards abutting against each other and movable laterally, 75 in combination with the keys and levers of the several sections, whereby when one lever is depressed all the others in the series are obstructed against depression.

6. In a voting apparatus, a series of individual-candidate sections, each provided with keys, levers and counters, a straight-ticket section provided with keys and levers, flattened 80 oscillating rods traversing all sections and operated by the straight-ticket keys, said rods 85 operating the aforesaid counters, means independent of said oscillating rods operated by the individual-candidate keys and operating the said counters, and in combination therewith, a series of pendulous pivoted disks 90 abutting against each other and movable laterally, and a pawl and ratchet-wheel actuated by the last disk of the series and a pin-stop for limiting the number of movements made by the pendulous wards and consequently the number of movements of the voting-keys.

7. In a voting apparatus, a series of sections; said sections provided with counters; respective individual-candidate keys for operating said counters; a straight-ticket section, said section provided with keys for operating such of said counters as were not previously cut out by substitution by said individual-candidate keys; and a rod to release 105 all levers operated.

8. In a voting apparatus, units or sections; said sections provided with voting-keys; traversing said sections a rod so placed that when turned it will obstruct or lock all said 110 keys whether or not any of said keys were operated.

9. In a voting apparatus, sections or units placed in series, each provided with voting-keys, levers and counters, oscillating rods 115 passing through all sections, but operated upon by the keys and levers of one section only, one of said rods locking the depressible keys of the other sections, mechanism for operating the counters by the movement of the 120 oscillating rods, and independent means for operating the said counters by the movement of the depressible keys of the other sections prior to the operation of said locking-rod, substantially as specified.

10. In a voting apparatus, sections or units placed in series each provided with depressible voting-keys, levers and counters, the said sections bearing the names of the individual candidates, mechanism between the keys and 125 counters for operating said counters, and means for locking the said levers when once operated until released by the resetting mechanism, a straight-ticket section provided with 130

keys, levers and bearing the names of the several parties to be voted for in straight ticket, independent mechanism, between the keys of the straight-ticket section and the counters in the individual-candidate sections, for operating the counters for all the candidates of said straight ticket not previously locked out.

11. In a voting apparatus, individual-candidate sections or units placed in series, each provided with depressible keys, levers, counters and bearing the names of individual candidates or measures, one section provided with keys, levers and bearing the names of the parties to be voted for in straight ticket, oscillating rods traversing all the sections but operated only by the keys of the straight-ticket section, independent means for operating the counters by the keys of the individual-candidate sections, means for locking the individual-candidate key-levers after one operation until all are reset by the resetting mechanism, means for locking all the keys of the individual-candidate sections against operation after a straight-ticket key has been operated, until reset, whether any of said individual-candidate keys were or were not previously operated.

12. In a voting apparatus, a series of straight-ticket keys, a series of individual-candidate keys, depressible levers corresponding to the individual-candidate keys, bell-cranks operated thereby, said bell-cranks provided with pawls to operate a corresponding register, and means comprising the stop-bar for preventing a second operation of the individual-candidate register by means of the straight-ticket keys, substantially as specified.

13. In a voting apparatus, sections or units placed in series, each provided with depressible voting-keys, levers and counters, one section bearing straight-ticket names, other sections bearing individual-candidate names, rods traversing all the sections for operating the counters therein, but operated only by the keys of the straight-ticket section, independent means for operating the counters by the keys of the individual-candidate sections, means for locking the individual-candidate key-levers after one operation until all are reset, means for locking all the keys of the individual candidates against operation after a straight-ticket key has been operated, whether prior or subsequent to the operation of one or more individual-candidate keys, means for preventing the operation of the counter, by a straight-ticket key, for any individual candidate whose key has been previously operated.

14. In a voting apparatus, the series of depressible keys 21, key-levers 37, with mechanism for acting on the counters, and the series of depressible keys 22, key-levers 53, oscillating bars 11, 12, 13, and 14, pawls 38, sliding bars 39, with mechanism for operating on the counters, in combination with the angular stop-bar 42, whereby the said sliding

bars are cut out from operation on the counters by the depression of individual-candidate keys 21, substantially as specified.

15. In a voting apparatus, a series of individual-candidate keys; a series of straight-ticket keys; a bar cooperating with said straight-ticket keys to lock the individual-candidate keys whether previously operated or not.

16. In a voting apparatus, the system of keys and counters, as herein described, a continuous grooved rod 9 that locks all the voting-keys which an elector has voted, a crank and sliding bar 27 to operate this rod, said sliding bar made angular at its end so as to disengage after moving a predetermined distance, substantially as described.

17. A series of levers, a series of interrupting-disks abutting against each other except the two that are separated by the depression of a lever, means to prevent voting more than once for the same candidate, and means to lock said levers against operation whether or not any lever of the series was operated.

18. The combination of a series of individual-candidate sections, each section comprising keys, levers, disks and counters; a straight-ticket section comprising keys, levers for operating the said counters, and disks; the said disks hung pendulous in the range of movement of the said levers so that when a lever is depressed said disks will be thrust laterally locking all unoperated levers of the series, and a rod passing underneath the individual-candidate keys, which, when partially revolved will lock said keys.

19. The combination of a series of individual-candidate sections comprising keys, tappets, levers, disks and counters; a straight-ticket section comprising keys, levers for operating said counters, and disks hung pendulous in the range of movement of said levers to prevent the operation of two or more levers at the same time; the disks of the individual-candidate sections hung pendulous in the range of movement of said tappets, so that when a tappet is depressed said disks will be thrust laterally to prevent the operation of more than one tappet at a time; means co-operating to limit or predetermine the number of times said tappets may be operated; means to detain all levers operated in their depressed condition until reset.

20. In a voting apparatus, an individual-candidate counter, means to operate said counter; additional means whereby said counter may be operated by either of two or more straight-ticket keys; in combination with a bar (as 42) for the purposes described.

21. In a voting apparatus, a series of sections, each provided with keys, levers and counters, a flattened locking-rod traversing all sections and so placed that when rocked it will lock all said keys subsequent to the operation of one or more of said keys.

22. In a voting apparatus, a series of sections, each provided with depressible voting-

keys, voting-numbers, names of respective candidates and corresponding counters; a straight-ticket section provided with names of parties and respective keys; flattened oscillating rods passing through all sections, each rod, respectively, operated by one of the said straight-ticket keys and operating the counters, in the individual-candidate sections, of the candidates composing the party ticket corresponding to the operated straight-ticket key; independent means controlled by the individual-candidate keys for operating said counters; in combination therewith a series of links, varied in length, connecting said levers with said rods, except one which is connected directly, the lever being slotted to accommodate the arc of movement.

23. In a voting-machine, two or more series of counters; individual-candidate keys for operating said counters irrespective of party; straight-ticket keys, rods operated by their respective ticket-keys to operate said counters in any of the series not operated by an individual-candidate key.

24. A series of straight-ticket levers, means for detaining the said levers, when operated, until reset, a series of interrupting-disks to prevent the operation of more than one lever of the series, a locking-rod operated by said levers, whereby the operation of a straight-ticket lever will lock the entire machine against further voting.

25. The combination of a series of individual-candidate keys for operating respective counters, a series of straight-ticket keys and levers for operating the same counters, an oscillating rod passing beneath all the individual-candidate keys and straight-ticket levers, a projection (as 71) in said levers, acting on said rod so that simultaneously with the operation of any of the straight-ticket keys, the said rod will lock all the individual-candidate keys against operation, whether said individual-candidate keys were operated or not.

26. A series of individual-candidate keys for operating respective counters, a series of straight-ticket keys and levers for operating the same counters, an oscillating rod passing beneath all the individual-candidate keys and straight-ticket levers, a projection (as 71) on said levers acting on said rod so that synchronously with the operation of any of the straight-ticket keys the said rod will lock all the individual-candidate keys against operation; in combination with means for detaining said straight-ticket levers in a depressed condition after operation, a series of hinged wards partially in the range of movement of said straight-ticket levers, whereby, when any one of said levers is depressed the said disks or wards will be thrust laterally thereby locking the unoperated levers against operation.

27. A series of individual-candidate keys for operating respective counters, a series of straight-ticket keys and levers for operating

the same counters, an oscillating rod passing beneath all the individual-candidate keys and straight-ticket levers, a projection (as 71) on said levers acting on said rod so that simultaneously with the operation of any of the straight-ticket keys the said rod will lock all the individual-candidate keys against operation, means for detaining the operated straight-ticket lever in a depressed condition, after operation, until reset; a series of hinged disks or wards partially in the range of movement of said straight-ticket levers, to lock the unoperated levers against depression, in combination with a rod indirectly connected with and partially turned by the opening of the entrance door of the room or booth, said rod unlocking the detents, thereby allowing the levers to resume their normal position.

28. In a voting apparatus, a deflected sliding bar 27, crank 26 and continuous locking-rod 9 that liberates or readjusts the voting mechanism after each elector has voted, substantially as described.

29. In a voting-machine two or more series of counters; individual-candidate keys for operating said counters; straight-ticket keys; rods operated by respective ticket-keys to operate said counters in any of the series not operated by said individual-candidate keys.

30. In combination with a voting-machine, an entrance - door; means for resetting the mechanism actuated by said entrance-door; means for voting for individual candidates irrespective of party; means for voting the remainder of any party-ticket by the operation of a single key.

31. In a voting-machine, an entrance-door and means for resetting the voting mechanism actuated by the said entrance - door; means for voting for individual candidates irrespective of party; means for limiting or predetermining the number of candidates that may be voted for in an office; means for voting the remainder of any party-ticket and locking the machine against further voting by the operation of a single key.

32. In a voting-machine, an entrance-door and means for resetting the voting mechanism actuated by said entrance-door; means to prevent voting for more than one candidate in an office; means for voting for individual candidates irrespective of party; means for voting the remainder of any party-ticket and simultaneously locking the machine against further voting by the operation of a single key.

33. A series of oscillating rods (as 11, 12, 13, and 14,) each provided with an adjustable cross-bar (as 62), levers (as 53), connected respectively with said rods by links (as 64 and 66), said levers provided with projections (as 71), which actuates a face-plate or bar (as 70) on rod (as 10), whereby the operation of any of the levers the said rod (as 10) will be oscillated or rocked simultaneously with the oscillation of said rods 11, 12, 13 or 14, accordingly as the lever of said rods, respectively, is operated.

34. A series of oscillating rods, transversely therewith a series of sliding bars provided with springs or flexible pawls, lugs on said sliding bars staggered in position to engage 5 with said rods respectively, and means for holding said pawls in a disengaged position.

35. A series of oscillating rods, transversely therewith a series of sliding bars provided with lugs staggered thereon to engage with 10 said rods as the exigency may require; a locking-rod, and means for rocking said locking-rod simultaneously with the operation of said oscillating rods.

36. A series of levers; means coöperating to 15 detain said levers when depressed; a series of pendulous disks abutting one against the other except the two that are separated by the depression of a lever, so as to lock the un-operated levers against depression; a bell- 20 crank adapted to be operated either by individual-candidate levers or by straight-ticket levers.

37. A series of individual-candidate levers with means for detaining said levers, when 25 operated, in a depressed condition until reset, a frame or wall with slots in which said levers project, said slots forming a guide for and limiting the range of movement of said levers, disks hung pendulous from said wall, 30 and in the range of movement of said levers, a series of interrupting-disks coöperating to prevent the depression of more than one lever of the series, and bell-cranks operable either by said levers or by straight-ticket key- 35 levers and connecting accessories.

38. A lever connected with a rod for operating individual-candidate counters, said lever provided with a slotted hole to accommodate the arc of movement, means on said 40 lever, comprising a projection thereon as described, to impart movement to a rod for locking the individual-candidate keys.

39. A series of rods; levers for operating said rods; links varied in length connecting 45 said rods with said levers; said levers provided with means to impart movement to a locking-rod.

40. A series of rods; levers for operating said rods; links varied in length connecting 50 said rods and levers; pendants to prevent the operation of more than one of said levers.

41. In a voting-machine, a series of individual-candidate counters with corresponding keys for operating the same; a series of straight-ticket keys for operating said counters; means whereby two or more of said straight-ticket keys may be connected with and operate any one of said individual-candidate counters; in combination with means 60 to prevent the operation of said counters more than once or more than one of the series.

42. In a voting-machine, means for voting for individual candidates irrespective of 65 party; means for voting the unvoted portion of any straight ticket by the operation of a straight-ticket key; and means for voting for

an individual candidate by either of two or more straight-ticket keys.

43. In a voting-machine, means for voting 70 for individual candidates irrespective of party; means for voting the unvoted portion of any straight ticket by the operation of a straight-ticket key; means for voting a straight ticket by said key; means for voting 75 for an individual candidate by either of two or more straight-ticket keys.

44. In a voting-machine, means for resetting the mechanism; means for voting for individual candidates irrespective of party; 80 means for voting the unvoted portion of any straight ticket by the operation of a straight-ticket key; means for voting for an individual candidate by either of two or more straight-ticket keys. 85

45. In a voting-machine, two or more series of counters; individual-candidate keys for operating the same irrespective of party, a face-plate or ballot containing the names of candidates and respective voting-numbers spaced 90 in harmony with said keys and counters; straight-ticket keys to operate said counters in any of the series not previously operated by an individual-candidate key; levers, operated by straight-ticket keys, with projections 95 (as 71) thereon to impart movement to a means for locking said individual-candidate keys whether previously operated or not; means to prevent operating a counter more than once or more than one counter of a series. 100

46. In a voting-machine, a multicandidate device comprising a ratchet-wheel 49 with fixed stop 51 thereon; pawls 50 and 50^a; disk 47, pin 52^a set in the path of movement of said stop 51, to limit the range of movement of said wheel 49 and therefore, to limit the number of movements of said pawl 50 whereby the number of votes that may be cast may be limited or predetermined, in combination with a rod adapted to release or reset the operated 110 parts; and a latch-bar to impart movement to said rod, said latch-bar adapted to be tripped after being moved a predetermined distance.

47. In a voting-machine, a series of individual-candidate counters with keys for operating the same; a face-plate or ballot containing the names of candidates, and spaced 115 in harmony with said keys and counters; voting-numbers to identify said keys and counters with said names; a separate series 120 of straight-ticket keys to operate said counters; a bar to cut out connection between said counters and said straight-ticket keys.

48. A series of levers connected with respective rods, said rods adapted to operate 125 the counters of individual candidates comprising straight-party tickets; a bar to cut out connection between said rods and said counters.

49. In a voting apparatus, a series of sections, each section provided with keys for operating corresponding individual-candidate counters; traversing said sections a series of rods, for operating said counters independ- 130

ently of said individual-candidate keys; said levers provided with means to impart movement to a locking-rod.

50. A series of sections, each containing a series of levers; pendants to prevent the operation of more than one lever at a time, a rod adapted to release the levers operated, said rod suitably connected with and adapted to be operated by a latch-bar, said latch-bar

10 so deflected as to trip after being moved a predetermined distance.

51. In a voting apparatus, means for rearranging for elections comprising a series of interchangeable sections, one for each office, each section containing counters and means for actuating the same of a number to correspond with the number of candidates for each office; a fixed straight-ticket section containing rods for operating said counters; said interchangeable sections provided with lugs whereby the counters contained therein may be operated by said rods.

52. A series of levers connected with rods for operating the counters of candidates comprising straight party-tickets; said levers provided with means to impart movement to a locking-rod; pendants to prevent the operation of more than one lever at a time.

53. A series of interchangeable sections containing means for voting for individual candidates irrespective of party, a straight-ticket section containing means for voting the remainder of any party-ticket not locked out by substitution, and the means to maintain said sections in their proper position.

54. A series of independent sections containing means for voting for individual candidates irrespective of party; a frame or support on which to rest said sections connected 40 with a section having keys for voting the remainder of any party-ticket.

55. The means for rearranging for elections comprising the operative elements for the candidates of each office disposed in independent and interchangeable sections; and a section containing means for operating said elements in all sections not previously operated or locked out by substitution; means to maintain said sections in their proper operative position.

56. A voting-machine capable of being rearranged to meet the requirements of succeeding elections, comprising a series of interchangeable individual-candidate sections, each section containing counters and keys for actuating the same; a straight-ticket section with keys for operating said counters; a rod for locking the individual-candidate keys; and a face-plate or ballot containing the names 55 of the candidates with voting-numbers adjacent, with or without the party designation, with or without names designating straight tickets, said face-plate or ballot spaced in harmony with said keys.

57. In a voting apparatus, a series of interchangeable sections, one for each office, each section containing individual-candidate

keys, counters and names of candidates with voting-numbers adjacent; traversing these sections a series of rods for operating said 70 counters independently of said individual-candidate keys; a rod for locking said keys against operation whether prior or subsequent to the operation of one or more of said keys; means for maintaining said sections in their 75 proper position.

58. In a voting apparatus, a series of interchangeable sections, one for each office, each section containing individual-candidate keys, counters and names of candidates with 80 voting-numbers adjacent; traversing said sections a series of rods for operating said counters independently of said individual-candidate keys; a rod for locking said keys against operation whether prior or subsequent 85 to the operation of one or more of said keys; means to limit or predetermine the number of candidates that may be voted for in an office; means for maintaining said sections in their proper position.

59. In a voting apparatus, a series of interchangeable sections, one for each office, each section containing individual-candidate keys, counters and names of candidates with voting-numbers adjacent; traversing said sections a series of rods for operating said counters independently of said individual-candidate keys; a rod for locking said keys against operation whether prior or subsequent to the operation of one or more of said keys; means 95 to prevent voting for more than one candidate in an office; means to prevent voting for a candidate more than once; means for maintaining said sections in their proper position.

60. In a voting apparatus, a bell-crank for operating an individual-candidate counter, said bell-crank operable by an individual-candidate key, or by a straight-ticket key, each independently of the other.

61. A series of bell-cranks for operating 110 corresponding counters, said bell-cranks operable by respective individual-candidate keys and by respective straight-ticket keys, each independently of the other.

62. A series of bell-cranks for operating 115 corresponding counters, said bell-cranks operable by respective individual-candidate keys or by either of two or more straight-ticket keys, in combination therewith means to prevent the operation of any of said bell-cranks more than once or of more than one thereof.

63. A series of interchangeable sections, each section containing a series of individual-candidate keys, a straight-ticket section containing a series of keys and means for retaining said interchangeable sections in their proper position; traversing all sections a rod for locking said individual-candidate keys simultaneously with the operation of any of 130 said straight-ticket keys.

64. In a voting-machine, a series of individual-candidate keys, a series of straight-ticket keys, means to prevent the operation

of a straight-ticket key and an individual-candidate key at the same time, said means comprising a rocking rod and a straight-ticket key-lever with a projection thereon adapted to impart movement to said rod.

65. A series of counters individual-candidate keys for operating said counters, a series of straight-ticket keys and levers for operating said counters, a rod passing beneath all the individual-candidate keys and straight-ticket levers, the latter having a projection thereon to impart movement to said rod, thereby locking all individual-candidate keys.

66. A series of levers, means coöperating to detain said levers when depressed, a series of pendulous disks abutting one against the other except the two that are separated by the depression of a lever, so as to lock the unoperated levers against depression; bell-cranks actuated by individual-candidate keys and connecting mechanism or straight-ticket keys and connecting mechanism, a stop-bar actuated by the individual-candidate key-levers to maintain the straight-ticket mechanism in a disengaged position.

67. In a voting apparatus, a series of sections, each containing individual-candidate keys, counters and names of candidates with voting-numbers adjacent; corresponding with said keys a series of bell-cranks adapted to operate said counters by the operation of said keys; through these sections rods for operating said bell-cranks, and consequently said counters, independently of said individual-candidate keys.

68. A series of bell-cranks; individual-candidate keys for operating said bell-cranks; straight-ticket keys for operating said bell-cranks; means to prevent the operation of more than one of the bell-cranks of the series by any of said keys, said means comprising a series of disks or wards to prevent the operation of more than one individual-candidate key, and a bar to cut out all said straight-ticket keys; or, said means comprising disks or wards to prevent the operation of more than one straight-ticket key and a rod or bar adapted to lock all the individual-candidate keys of the series, accordingly as the individual-candidate key or the straight-ticket key is first operated.

69. A series of bell-cranks operable either by individual-candidate key-levers or by straight-ticket key-levers; a bar as described to prevent the operation of any bell-crank of the series by said straight-ticket key-levers subsequent to the operation of any one thereof by said individual-candidate key-levers.

70. In a voting apparatus, an individual counter means to operate said individual-candidate counter; additional means whereby said counter may be operated by either of two or more straight-ticket keys.

71. In a voting-machine, individual-candidate counters; respective keys for operating said counters; straight-ticket keys for operating said counters; means to prevent the op-

eration of any of said counters more than once by said keys.

72. In a voting-machine, a cover to conceal and protect the mechanism; candidate-counters; respective individual-candidate keys for operating said counters; voting-numbers to identify said keys with said counters; straight-ticket keys to operate said counters independently of said individual-candidate keys.

73. In a voting-machine; candidate-counters; respective individual-candidate keys for operating said counters; voting-numbers to identify said keys and counters; straight-ticket keys for operating said counters independently of said individual-candidate keys.

74. In a vote-recording machine, means for resetting the mechanism, comprising a rod adapted to release or reset the operated parts; connected with said rod a deflected latch-bar; a guide for said latch-bar so set as to trip said latch-bar when moved a predetermined distance; means to impart movement to said latch-bar, substantially as described.

75. In a voting-machine, a series of counters; individual-candidate keys to operate said counters; straight-ticket keys to operate said counters; a bar operated by said individual-candidate keys to prevent the operation of said counters by any of said straight-ticket keys when operated.

76. In a voting-machine, a series of counters; individual-candidate keys to operate said counters; straight-ticket keys to operate said counters independently of said individual-candidate keys; a bar operated by said individual-candidate keys to prevent the operation of said counters by any of said straight-ticket keys when operated.

77. In a voting-machine, a series of counters; individual-candidate keys to operate said counters; straight-ticket keys to operate said counters; a bar operated by said individual-candidate keys to prevent the operation of said counters by any of said straight-ticket keys when operated; a rod coöperating with said straight-ticket keys to lock said individual-candidate keys.

78. In a voting-machine, a series of counters; individual-candidate keys to operate said counters; voting-numbers to identify said keys and counters; straight-ticket keys to operate said counters; a bar, operated by said individual-candidate keys, to prevent the operation of said counters by any of said straight-ticket keys when operated.

79. In a voting-machine, a series of counters; individual-candidate keys to operate said counters; voting-numbers to identify said keys with said counters; straight-ticket keys to operate said counters independently of said individual-candidate keys; a bar operated by said individual-candidate keys to prevent the operation of said counters by any of said straight-ticket keys when operated.

80. In a voting-machine, keys for voting for individual candidates irrespective of party;

means, independent of said keys, for voting the remainder of any party-ticket.

81. In a voting-machine, keys for voting for individual candidates irrespective of party; means independent of said keys, for voting the remainder of any party-ticket at a single operation.

82. In a voting-machine, a series of rods; transversely therewith a series of sliding bars; said bars provided with lugs, said lugs staggered on said bars to engage with said rods as the exigency may require; flexible pawls on said bars; a bar to depress said pawls.

83. In a voting-machine, segregable sections; said sections containing keys for voting for individual candidates irrespective of party; means, independent of said keys, for voting the remainder of any party-ticket.

84. In a voting-machine, a series of individual-candidate sections, comprising keys and levers for operating respective counters; a straight-ticket section provided with keys and levers for operating said counters; traversing said sections an oscillating rod adapted to release all levers operated; in combination therewith a bar to prevent the operation of the counters, in an individual-candidate section wherein one of the counters has been operated by an individual-candidate key, by said straight-ticket key-levers.

85. In a voting-machine, means to operate an individual-candidate counter by either of two or more straight-ticket keys.

86. In a voting-machine, a series of counters; individual-candidate keys to operate said counters; means whereby any of said counters may be operated by either of two or more straight-ticket keys.

87. In a voting-machine, a series of individual-candidate keys; a rod for locking said keys against operation; a series of straight-ticket levers with projections thereon to impart movement to said rod; a series of wards to prevent the operation of more than one of said levers at a time, substantially as described.

88. In a voting apparatus, a series of sections; said sections provided with counters; respective individual-candidate keys for operating said counters; a straight-ticket section; said section provided with keys for operating such of said counters as may comprise a straight ticket, or the unvoted portion thereof, independently of said individual-candidate keys.

89. In a voting apparatus, a series of individual-candidate counters; respective individual-candidate keys to operate said counters; straight-ticket keys to operate said counters; means whereby said counters may be operated by either of two or more of said straight-ticket keys; in combination with means to prevent the operation of any of said counters more than once, or of more than one of the series, by any of said keys, substantially as described.

90. In a voting-machine, the means for voting a split ticket, comprising individual-candidate keys; ticket-keys; means coöperating with the inwardly portion of said keys whereby a portion of said split ticket may be voted by said candidate-keys and a portion of said split ticket may be voted by said ticket-keys.

91. In a voting-machine, a casing to contain the mechanism; individual-candidate counters; candidate-keys to operate said counters; ticket-keys to operate said counters, said keys operating partially within and partially without said casing and so projecting therefrom that said keys may be operated; mechanism coöperating with the inwardly portion of said keys whereby the whole or a portion of such of said counters as comprise a party-ticket may be operated by the operation of one of said ticket-keys.

92. In a voting-machine, a casing to contain the mechanism; individual-candidate counters; candidate-keys to operate said counters; ticket-keys to operate said counters, said keys operating partially within and partially without said casing and so projecting therefrom that said keys may be operated; mechanism coöperating with the inwardly portion of said keys whereby the whole or a portion of such of said counters as comprise a party-ticket may be operated by the operation of one of said ticket-keys; mechanism to prevent voting for a candidate more than once.

93. In a voting-machine, a casing to contain the mechanism; individual-candidate counters; candidate-keys to operate said counters, said keys operating partially within and partially without said casing and so projecting therefrom that said keys may be operated; party-keys; mechanism coöperating with the inwardly portion of said keys whereby the whole or a portion of such of said counters as comprise a party-ticket may be operated by the operation of one of said ticket-keys; means to prevent voting for more than one candidate in an office.

94. In a voting-machine, a casing to contain the mechanism; individual-candidate counters; candidate-keys to operate said counters, said keys operating partially within and partially without said casing and so projecting therefrom that said keys may be operated; mechanism coöperating with the inwardly portion of said keys whereby the whole or a portion of such of said counters as comprise a party-ticket may be operated by the operation of one of said ticket-keys; mechanism to limit or predetermine the number of candidates that may be voted for in an office.

95. In a voting-machine, the means for voting a split ticket, comprising a casing, candidate-keys, ticket-keys, said keys partially projecting and partially within said casing, means, coöperating with the inwardly portion of said keys, whereby a portion of said split ticket may be voted by said candidate-keys and a portion thereof by said ticket-keys.

96. In a voting-machine, means for voting for individual candidates irrespective of party; ticket-keys; mechanism for voting the portion of any party-ticket, not otherwise voted, by the operation of one of said keys; said mechanism so disposed as to be operable only through the medium of said ticket-keys.

97. In a voting-machine, means for voting for individual candidates irrespective of party; ticket-keys; mechanism for voting the portion of any party-ticket, not otherwise voted, by the operation of one of said keys; said mechanism so disposed as to be operable only through the medium of said ticket-keys; means to prevent voting for a candidate more than once; means to prevent voting for more than one candidate in an office; means to limit or predetermine the number of candidates that may be voted for in an office; means to reset the operated parts, substantially as described.

98. In a voting-machine, a casing; ticket-keys; said keys operating partially within and partially without said casing and so projecting therefrom that said keys may be operated; means coöperating with the inwardly portion of said keys whereby the whole or a portion of a party-ticket may be voted by the operation of a ticket-key.

99. In a voting-machine, ticket-keys; mechanism coöperating therewith whereby the whole or a portion of a party-ticket may be voted by one of said keys; means whereby a candidate may be voted for by either of two or more of said keys.

100. In a voting-machine, candidate-keys; ticket-keys; and mechanism so disposed as to prevent removal of the parts thereof coöperating with said keys, whereby a portion of a split ticket may be voted by said candidate-keys and a portion thereof by said ticket-keys.

101. In a voting-machine, the means for voting a split ticket, comprising counters for individual candidates; corresponding keys for operating said counters; ticket-keys for operating said counters; mechanism coöperating with said keys whereby a portion of said split ticket may be accumulated on said counters by said individual-candidate keys, and a portion thereof by said ticket-keys, said mechanism so disposed as to prevent the operation of said coöperating mechanism, or any of the parts thereof, except by said keys.

102. In a voting-machine, the means for voting a split ticket, comprising a casing, candidate-keys, ticket-keys, said keys partially projecting and partially within said casing, means coöperating with the inwardly portion of said keys, whereby a straight ticket may be voted by said ticket-keys, or whereby a portion of said split ticket may be voted by said candidate-keys and a portion thereof by said ticket-keys.

In testimony whereof I have hereunto affixed my signature in the presence of two witnesses.

A. J. BOLFING.
